US0D1037855S

(12) **United States Design Patent** (10) **Patent No.:** **US D1,037,855 S**
(45) **Date of Patent:** **** Aug. 6, 2024**

(54) **BOTTLE**

(71) Applicant: **Diageo North America, Inc.**, New York, NY (US)

(72) Inventors: **Christopher Jenkins**, London (GB); **William Dohm**, Gurnee, IL (US)

(73) Assignee: **DIAGEO NORTH AMERICA, INC.**, New York, NY (US)

(**) Term: **15 Years**

(21) Appl. No.: **29/796,707**

(22) Filed: **Jun. 25, 2021**

(51) LOC (14) Cl. **09-01**

(52) U.S. Cl.

USPC **D9/553**

(58) **Field of Classification Search**

(57) **CLAIM**

The ornamental design for a bottle, as shown and described.

DESCRIPTION

FIG. 1 is a front perspective view of the bottle showing our new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The broken lines shown in the drawings are for the purpose of illustrating parts of the article that form no part of the claimed design. The dash-dot-dash broken lines illustrate boundaries that form no part of the claimed design.

1 Claim, 5 Drawing Sheets
